UNITED STATES PATENT OFFICE.

ROBERT HENRY JEFFREY, OF GABRIEL, MEXICO.

ORE FLOAT-SEPARATOR.

1,052,061.

Specification of Letters Patent.

Patented Feb. 4, 1913.

Application filed August 23, 1910. Serial No. 578,583.

To all whom it may concern:

Be it known that I, ROBERT HENRY JEFFREY, a subject of the King of Great Britain, and a resident of Gabriel, Durango, Mexico, have invented certain new and useful Improvements in Ore Float-Separators, of which the following is a specification.

My invention relates generally to ore float separators and is designed to take advantage of the well known tendency of dry metallic particles, when finely ground, to float upon the surface of a liquid. By bringing about and utilizing this condition, complete separation of metals carrying values from their ores or gangue in which they are contained, may be economically effected.

The present invention relates more particularly to certain improvements in the apparatus described and illustrated in my pending application, serially numbered 550,703 and filed March 21, 1910, in which provision is made for giving the surface liquid in a containing tank or vessel, motion from the center thereof, outward to an overflow at the periphery and further for delivering and distributing the dry metallic particles, in a finely divided state, over the various surface of the liquid, to effect a separation by the method above referred to. In my prior application, the means disclosed for imparting motion to the surface liquid in the tank, is shown and described as a rose nozzle, fitted to the outlet end of a liquid supply pipe and relatively arranged to discharge the liquid laterally in all directions. I have found that by modifying the construction and arrangement of the rose nozzle, better results are obtained and to this end, I cap the same in a manner to direct the liquid downward at a suitable angle and then direct it laterally by means of a conical disk deflector, which may be adjusted relatively to the nozzle, as conditions may require.

The accompanying drawings will serve to illustrate apparatus suitable for carrying my invention into effect. I wish it understood, however, that I do not limit myself to the exact construction or arrangement of parts shown and described, as various changes may be made within the meaning of the present invention.

In the drawings: Figure 1 is a view in perspective of my improved ore separating apparatus. Fig. 2 is a detailed sectional view of the jet pipe and deflector.

Referring now to the drawings, 1 represents a liquid containing tank or vessel in the form of an inverted cone. A water pipe 2, from any suitable source of supply, terminates in branches 3 and 4, which are run into the tank and arranged to deliver at points at or near the bottom and top thereof. The branch 3, delivering at the bottom of the conical tank, may be tangentially disposed therein, turned upward or otherwise arranged to maintain sufficient force or in-rush, to act as a cushion to prevent the ore settling too rapidly toward the outlet valve 5, and at the same time keep the water in the tank at a proper level. The water intended to float the metallic particles, is supplied by the branch 4, which terminates just above the surface of the liquid in the tank, in a nozzle 6, shaped to discharge a circular jet. The nozzle 6, is capped as indicated by an approximately semi-spherical shell 7, which serves to direct the circular jet from the nozzle, downward at a suitable angle and it is thereafter deflected outward, in the plane of the surface of the liquid in the tank, by a conical disk 8. By means of a screw-thread connection indicated at 9, the conical disk 8 may be adjusted relatively to the circular jet, as conditions may require. The screw threads may be formed directly on the branch pipe 4 or as indicated on a sleeve 10, inclosing the pipe.

Mounted above the tank 1, there is a hopper 11, preferably of inverted cone-shape, having an outlet 12^a at the bottom, which is controlled by a valve 12. The valve 12 is mounted on a shaft 13, which, is geared to be driven by a belt pulley 14 on a shaft 15. The opening and closing of the valve is controlled by a hand-wheel 16 on shaft 17. The construction and arrangement of the gearing, shafting, etc., for rotating and controlling this valve is fully described in my prior application referred to and as the same is not claimed herein, it will not be further described.

In the use of the apparatus, the ore is fed to the hopper 11, from which it is discharged by means of rotating valve 12, which may be so adjusted as to feed the material steadily to the surface of the water or the conical disk 8, in the tank below or to discharge it so that it impinges on the surface of the water or the disk from a suitable height and angle.

In the operation of the apparatus, the surface of the liquid in the separator is given a conical form by the disk 8 and through the arrangement of the conical spray device 5 6-7, a constant flow is maintained radially outward in all directions. The finely divided ore, falling thereon, is quickly and rapidly disposed of, the lighter valuable particles being carried outward to the periphery of the tank, there to be collected in 10 a launder 18, and thereafter settled by suitable means, while the heavy coarse metallic particles together with barren material, sink through the water to the bottom of the tank 15 and may be drawn off through the valve and subsequently treated. This result is obtained only when there is an even distribution of the ore upon the conical surface of the liquid in the tank and further, as ore 20 differs materially, the result is also dependent more or less upon the angle at which the particles strike the surface. The skipping of the stones over the surface of water may be cited as illustrating this last 25 mentioned action, since unless thrown at the proper angle, stones both light and heavy will be driven below the surface.

The important advantages of the peculiar feeder herein disclosed will be apparent. 30 In addition to effecting equal distribution of the ore particles over the surface of the liquid in the separator tank, it is adjustable vertically to permit the angle of fall of such particles to be varied as may be required, 35 depending upon the particular run of ore being separated.

It is found that the addition of a small percentage of oil or saline solution to the water in the tank, causes the metallic particles in 40 certain cases to float more freely and in such instances, may be used to advantage. It is also found that the use of liquids heavier than water in some cases, increases the extraction.

45 Having, therefore, described my invention, I claim:

1. An ore-float separator containing a

body of liquid, means giving the effective surface of the liquid conical form, a centrally disposed liquid supply delivering the liquid radially outward in all directions, an ore distributor above the liquid and adjustable to and from the liquid surface, and means for imparting rotary motion to the ore distributor.

55

2. An ore-float separator containing a body of liquid, a conical member rising from the surface of the liquid, means maintaining a flow of liquid radially outward in all directions over the surface of the conical member, an ore distributor above the member and adjustable to and from said member to vary the angle of impingement, and means for imparting rotary motion to the ore distributor.

65

3. An ore-float separator containing a body of liquid, a conical member rising from the surface of the liquid, means maintaining a flow of liquid radially outward in all directions over the surface of the conical member, a valved hopper above the member, and means for simultaneously rotating and adjusting the valve, said hopper and valve being slightly above the flowing liquid, and said valve adjustment being adapted to vary the angle of impingement of material upon the flowing liquid.

70

4. An ore-float separator containing a body of liquid, a conical member rising from the surface of a liquid, means maintaining a flow of liquid radially outward in all directions over the surface of the conical member, a valved hopper above the member and slightly spaced therefrom, a shaft carrying the valve of the hopper and means for simultaneously imparting rotary and longitudinal motion to the shaft and the valve carried thereby.

80

Signed at New York, N. Y. this 16th day of August A. D. 1910.

ROBERT HENRY JEFFREY.
